(57) **CLAIM**

The ornamental design for a direct superior retractor handle, as shown and described.

DESCRIPTION

The present application is related to U.S. Design application Ser. No. 29/623,700, filed concurrently herewith, the entire disclosure of which is incorporated herein by reference.

FIG. 1 is a front perspective view of a direct superior retractor handle according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a bottom perspective view thereof.

The broken lines shown in the drawings are for the purpose of illustrating environmental structure and form no part of the claimed design. The dot-dash broken lines define the bounds of the claimed design and form no part thereof. The claimed design extends to but does not include the boundary line.
